Fig. 1

Fig. 2

Fig. 4

FIG. 1 is an elevational view of a candlestick showing my new design;

FIG. 2 is a top plan view taken along the line 2—2 of FIG. 1;

FIG. 3 is a bottom plan view; and

FIG. 4 is a fragmentary perspective view taken from the opposite side of FIG. 1 with the base omitted for ease of illustration.

The characteristic feature of my design for a candleholder resides in the appearance of the cup member in combination with the footed base as shown.

I claim:

The ornamental design for a candlestick, as shown and described.
